UNITED STATES PATENT OFFICE

ALFRED W. ANDERSON, OF OAK PARK, ILLINOIS

SUTURE SUPPORTING AND ATTACHING PLATE

Application filed April 22, 1931. Serial No. 531,941.

This invention relates to suture supporting and attaching plates adapted for use in the practice of surgery, in the closing of wounds or incisions.

It is general practice to pass a suture through the skin adjacent an incision, downwardly through the fatty and muscular layers, by means of a curved needle, then upwardly through said layers and the skin at the opposite side of the incision, to draw the edges of the skin together and then tie the ends of the suture into a knot. The knotted suture thus crosses the incision and rests on the sensitive skin adjacent the wound. In the event any swelling takes place after the suture has been applied, no means are provided for relieving the strain and the discomfort of the patient. Another objection to the practice referred to is the difficulty of cleansing a wound so sutured, and the danger of infections.

The object of the present invention is to provide a suture supporting and attaching plate which will permit of adjustment of the suture as often as desired after it has been applied. Another object is to produce a device which, without bearing on the skin adjacent the incision, will support the suture in such manner that it will not bear on the wounded region. Another object is to provide a device of the character described which will permit free circulation of air adjacent the wound and will facilitate cleansing of the parts.

In the drawings—

Fig. 1 is an enlarged perspective view of a suture supporting and attaching plate embodying my invention.

Fig. 2 is a plan view of the device as it appears in use.

Fig. 3 is a transverse vertical section taken on the line 3—3 of Fig. 2.

Fig. 4 is a longitudinal vertical section taken on the line 4—4 of Fig. 2, looking in the direction indicated by the arrows.

Fig. 5 is a blank from which the device of Fig. 1 is formed.

Fig. 6 is a transverse vertical sectional view of a modified form of the invention.

Fig. 7 is a blank from which the modified form of device shown in Fig. 6 is formed.

In the drawings a device embodying the invention is shown in position on the skin 10 of a patient, and the fatty and muscular layers beneath the skin are indicated at 11 and 12. An incision is indicated at 13.

In that embodiment of the invention shown in the drawings, the suture supporting and attaching plate comprises a base which may be substantially flat or shaped to be complementary to the surface 10 on which it is intended to rest. The base consists of two oppositely facing, L-shaped members, the arms 14 of which are intended to extend parallel to, and the arms 15 at right angles to, the incision 13. These L-shaped base members are connected together in spaced apart relation by an upwardly projecting wall 16 which is preferably integral with the arms 15 of the base and rises from the inner edges of said arms 15. The upright wall 16 is preferably cut away as indicated by the curved line 17, at the part between the arms 15.

The wall 16 supports a horizontally disposed member 18 which is the suture attaching plate. The plate 18 is provided on its longitudinally extending free margin with narrow slits 19 which extend inwardly from said free edge. The slits 19 at each side of the center extend diagonally inwardly and toward opposite end margins of the plate 18. Adjacent each end the plate 18 is cut to form tongues 20 bent slightly upwardly from the plate 18. 21 indicates an aperture in the walls 16 and 18.

As best shown in Fig. 3, the wall 16 is inclined so as to overhang the arms 15 of the base to some extent in order to bring the slit edge of the plate 18 substantially midway between the margins 22 and 23 of the device.

The under surface of the base members 14 and 15 may be provided with ridges 24 which extend transversely of the device and parallel to the incision 13 when the plate is in the position shown in Fig. 4. These ridges 24 project downwardly and inwardly, that is, toward the transverse median line of the device.

In using my invention, the suture 25 is applied in the usual manner so that the ends emerge from the skin 10 at opposite sides of the incision 13. The ends 25' are drawn to-

- 5 toward each other to bring the incision edges together and then the suture supporting and attaching plate is placed into position, with the base arms 14 parallel with the incision and located slightly outwardly of the 10 points where the sutures 25' emerge from the skin. The ridges 24 assist in urging the skin and flesh at opposite sides of the incision toward each other. In this position no part of the base or of the upwardly extending wall 15 16 is in contact with the incision or with the points where the sutures emerge from the skin. The free edge of the plate 18 is spaced from the wound and is substantially directly 20 above a line extending across the incision and through the points where the sutures emerge.

The surgeon preferably grasps the device and holds it in position by an instrument which engages the plate 18 adjacent the aperture 21. The suture ends 25' are inserted 25 through slits 19 at opposite sides of the center of the edge of the plate 18 and are then passed under the tongues 20 on top of the plate 18 as best shown in Figs. 2 and 4. In this manner the sutures are supported out of 30 contact with the wound and are adjustably and removably held in desired position and may be readily loosened and reattached.

The device may be made in various sizes, it being intended that the base arms be spaced 35 apart sufficiently to accommodate the sutures inwardly of said arms, and the distance between the margins 22 and 23 being substantially equal to the distance between adjacent sutures.

40 In Figs. 6 and 7 I have illustrated a modified form of the invention in which the parts are identical with those heretofore described, excepting that the free edge of the plate 18, near its ends, is provided with legs 26 to aid 45 in supporting the attaching plate 18 and to render the device as a whole, firm and reliable. The legs 26 extend downwardly and at their lower ends are provided with feet 27 which rest on the skin 10.

50 From the foregoing description it will be apparent that the parts adjacent the incision are not in direct contact with the suture supporting and attaching plate and that the wound may be kept perfectly clean and infections avoided; also that while the suture 55 ends are drawn toward each other sufficiently to close the wound, they are not knotted together and are attached to the plate 18 in such manner that they may be easily loosened in the event swelling occurs, and thereby the patient is rendered comfortable.

Changes may be made in details of construction without departing from the scope of my invention and I do not intend to be 60 limited to the exact form shown and de-

scribed, except as set forth in the appended claims.

I claim—

1. A suture supporting and attaching device comprising a base consisting of two oppositely facing substantially L-shaped members, a substantially upright wall connecting said L-shaped members together in spaced apart relation, and a suture attaching plate carried by said wall in a plane above 70 the base members.

2. A suture supporting and attaching device comprising a base and a suture attaching plate mounted on the base, said plate being provided on one margin with slits and 80 on its top with tongues adapted to receive and frictionally hold said suture ends.

3. A suture supporting and attaching device comprising spaced apart base members and a suture attaching plate mounted on said 85 base members and extending across the space between said members, said plate being provided on one margin with slits and on its top with tongues adapted to receive and frictionally hold said suture ends. 90

4. A suture supporting and attaching device comprising a base consisting of two oppositely facing substantially L-shaped members, a substantially upright wall connecting 95 said L-shaped members together in spaced apart relation, and a suture attaching plate carried by said wall in a plane above the base members, said plate being provided on one margin with slits and on its top with 100 tongues adapted to receive and frictionally hold said suture ends. 100

5. A suture supporting and attaching device comprising a base and a suture attaching plate mounted on the base, said base being provided on its under surface with ridges 105 which extend transversely of the device and project downwardly and inwardly toward the center of the device.

6. A suture supporting and attaching device comprising spaced apart base members and a suture attaching plate mounted on said 110 base members and extending across the space between said members, said base being provided on its under surface with ridges which extend transversely of the device and project downwardly and inwardly toward the center of the device. 115

7. A suture supporting and attaching device comprising a base consisting of two oppositely facing substantially L-shaped members, a substantially upright wall connecting 120 said L-shaped members together in spaced apart relation, and a suture attaching plate carried by said wall in a plane above the base members, said base being provided on its under surface with ridges which extend transversely of the device and project downwardly and inwardly toward the center of the device. 125

8. A suture supporting and attaching plate 130

comprising base members extending substantially parallel to each other and spaced apart a distance sufficient to rest on the skin at each side of an incision and outwardly of the points where the suture emerges from the skin, and a suture supporting plate mounted on said base members in a plane above the same and adapted to extend from one base member to the other across the incision without contacting with the skin, said plate being provided with means for detachably engaging the suture ends.

9. A suture supporting and attaching plate comprising base members extending substantially parallel to each other and spaced apart a distance sufficient to rest on the skin at each side of an incision and outwardly of the points where the suture emerges from the skin, and a suture supporting plate mounted on said base members in a plane above the same and adapted to extend from one base member to the other across the incision without contacting with the skin, said plate being provided with means for detachably engaging the suture ends, said means consisting of a plurality of slits extending diagonally inwardly from one margin of the plate.

10. A suture supporting and attaching plate comprising base members extending substantially parallel to each other and spaced apart a distance sufficient to rest on the skin at each side of an incision and outwardly of the points where the suture emerges from the skin, and a suture supporting plate mounted on said base members in a plane above the same and adapted to extend from one base member to the other across the incision without contacting with the skin, said plate being provided with means for detachably engaging the suture ends, the base members being provided on their lower surfaces with ridges projecting diagonally toward the incision when the device is in use.

45 11. A suture supporting and attaching plate comprising base members spaced apart a distance sufficient to rest on the skin at each side of an incision and outwardly of the points where the suture emerges from the skin, and a suture supporting plate mounted on said base members in a plane above the same and adapted to extend from one base member to the other across the incision without contacting with the skin, said plate being provided with means for detachably engaging the suture ends.

12. A suture supporting and attaching plate comprising base members spaced apart a distance sufficient to rest on the skin at each side of an incision and outwardly of the points where the suture emerges from the skin, and a suture supporting plate mounted on said base members in a plane above the same and adapted to extend from one base member to the other across the incision with-

out contacting with the skin, said plate being provided with means for detachably engaging the suture ends, said means consisting of a plurality of slits extending inwardly from one margin of the plate.

13. A suture supporting and attaching plate comprising base members spaced apart a distance sufficient to rest on the skin at each side of an incision and outwardly of the points where the suture emerges from the skin, and a suture supporting plate mounted on said base members in a plane above the same and adapted to extend from one base member to the other across the incision without contacting with the skin, said plate being provided with means for detachably engaging the suture ends, the base members being provided on their lower surfaces with ridges projecting diagonally toward the incision when the device is in use.

14. A suture supporting and attaching plate comprising spaced apart base members adapted to rest on the skin of a patient at opposite sides of an incision, a raised plate mounted on said base members extending from one to the other, and means on said plate for holding the suture ends without the necessity of tying said ends together and for permitting detachment of said sutures without cutting the same.

In testimony that I claim the foregoing as my invention, I affix my signature, this 20th day of April, 1931.
